UNITED STATES PATENT OFFICE.

WILLIAM FEHLHABER AND CHARLES L. SMITH, OF HIGHLANDS, NEW JERSEY.

FASTENER FOR THE TIPS OF BILLIARD-CUES.

1,362,483.

Specification of Letters Patent. Patented Dec. 14, 1920.

Application filed September 3, 1919. Serial No. 321,440.

To all whom it may concern:

Be it known that we, WILLIAM FEHLHABER and CHARLES L. SMITH, citizens of the United States, residing at Highlands, in the county of Monmouth and State of New Jersey, have invented new and useful Improvements in Fasteners for the Tips of Billiard-Cues, of which the following is a specification.

10 This invention relates to an improved fastener for the tips of billiard cues.

The principal objects in view are to provide for fastening the tip without the use of glue and in such manner that there is no 15 weakening of the cue, that the tip is held with the utmost security and rigidity and is not susceptible to any loose play, and that the tip may be readily and quickly applied to or removed from the cue.

20 With the above objects in view, the invention consists of certain novel features of structure and combination which will be set forth at length as the description proceeds.

An embodiment of the invention is illustrated in the accompanying drawings wherein:

Figure 1 is an elevation of a cue having a tip secured thereto by the fastening means of the present invention.

30 Fig. 2 is a central vertical sectional view, the tip being shown in elevation.

Fig. 3 is a similar view in a plane at right angles to the plane of Fig. 2.

Fig. 4 is a detail sectional view on the 35 line 4—4 of Fig. 3.

Figs. 5 and 6 are detail horizontal sectional views on the lines 5—5 and 6—6 of Fig. 3 looking in the direction of the arrows.

40 Figs. 7 and 8 are detail perspective views of inclosed elements of the fastener.

Similar characters of reference designate corresponding parts throughout the several views.

The cue A carries at its outer end a projecting ferrule 1 which is externally flush with said cue and which is preferably formed with internal threads 2. These are essentially provided in connection with the securing of the tip B but are preferably 45 also utilized for the attachment of the ferrule to the cue and are so shown. Accordingly, the threads 2 in the preferred construction are continued throughout the length of the ferrule and are engaged with a projecting tenon a at the end of the cue A. In practice, the tenon a may be left smooth-

surfaced and the ferrule 1 may be used by virtue of its threads 2 to cut the coöperating threads on said tenon. An external annular shoulder a' at the junction of the tenon a 60 and the cue body provides a bearing or seat for the adjacent end of the ferrule.

The tip B, which may be of any material having the desired cushioning properties, leather being the material most frequently employed, has a ball-engaging portion b located beyond the end of the ferrule and of the ordinary form. Said tip also has a reduced axial extension b' which is relatively hard; in the case of leather, the material of 70 this extension may be treated in any suitable and known manner to secure the desired hardness. At the junction of the engaging portion b and the extension b' an annular shoulder b² is provided which has a 75 flat and uniform bearing or seating against the adjacent end of the ferrule. The extension b' preferably has engagement with the threads 2 of the ferrule. Preferably, said extension is left smooth-surfaced and, as 80 turned into the ferrule, threads are cut thereon by the threads 2. In order to hold the tip B against accidental turning movement, one or more notches may be provided in the surfaces of the ferrule which are in contact 85 with the tip. As shown and preferred, a notch 3 is cut in the outer edge of the ferrule and an adjoining notch 4 is cut longitudinally in the threaded portion of the ferrule. These notches have substantially perpendicular walls which, considering the resiliency nature of the material of the tip B, function similarly to retaining pawls in holding said tip against accidental turning movement; however, said notches offer no 90 appreciable resistance to the turning manipulation of the tip, when it is desired to remove the same from the ferrule.

The shoulder b² and the threaded engagement of the extension b' assure of the rigidity 100 of the tip with reference to the ferrule; and such rigidity is made permanent by the employment of fastening parts which act independently of the extension b' in the retention of the ferrule and which also relieve 105 the threads of said extension from any stresses. These fastening parts hold the tip positively and with great security in the ferrule and comprise a block 5 and connecting arms 6 which secure the tip to the block. 110 The block 5 is preferably of oblong outline and its dimension of greatest length con-

forms to the internal diameter of the ferrule. Its vertical end faces are provided with threads 7 for engagement with the threads 2 and its side faces 8 are preferably parallel. 5 The arms 6 are associated with the block 5 to bind the tip thereto and in such way that they may be moved to provide for the disconnection of the block and the tip as occasion may require. In the construction preferred 10 said arms are connected in pairs by a straight bow 8 which functions as a pivot bar and has a seating in a transverse recess 9 in the under face of the block 5. Two pairs of arms 6 so connected and associated 15 with said block are provided for engagement with the tip at opposite sides thereof. At their terminals the arms 6 are provided with angular gripping portions 10 which engage in recesses 11 in the extension b' , these recesses being formed as radial and inward 20 extensions of longitudinal recesses 12 cut into the surface of the extension b' for a depth sufficient to enable the arms 6 to be swung in clear of the threads 2. If desired, the walls of the grooves 9 may be upset 25 to provide against the separation of the arms 6 and the block 5. The under face of the extension b' preferably has a flat and uniform bearing against the upper face of 30 the block 5, further insurance of the rigidity of the tip B relatively to the ferrule being thus provided.

The securing or removal of the tip may be effected readily and quickly.

35 The tip, prior to its attachment to the ferrule, is first connected to the block 5 by means of the arms 6. These arms which lie at the sides of the block 5 are swung relatively inward to engage their angular terminals 10 in the recesses 11 and so bind the tip in position upon the block. As thus connected together, the tip and the block form a unit which may be inserted into or removed from the ferrule by simply turning 40 the tip in the appropriate direction to insure that the coöperating threads of the unit shall feed inward or outward relatively to the threads 2. In inserting the unit the tip is turned to feed the block 5 inward into the 45 ferrule and to produce a like effect upon its extension b' until its shoulder b^2 has relatively strong frictional contact with the adjacent end of the ferrule. At such time, the notches 3 and 4 act in the manner described 50 to prevent the accidental turning movement of the tip in the reverse direction.

Having fully described our invention, we claim:

60 1. In a billiard cue tip-fastener, the combination of a ferrule projecting from the cue and having internal threads, a tip formed to have a bearing against the end of the ferrule, a block having faces provided with threads for engagement with said internal

threads and means having a bearing on the lower and side faces of said block detachably connecting said tip and said block to provide for their manipulation as a unit relatively to the ferrule.

2. In a billiard cue tip-fastener, the combination of a ferrule projecting from the cue and having internal threads, a tip having a shoulder to bear against the end of the ferrule and also having an extension within the ferrule for engagement with said threads, a block having faces provided with threads for engagement with said internal threads and means partially surrounding said block and detachably connecting said tip and said block to provide for their manipulation as a unit relatively to the ferrule.

3. In a billiard cue tip-fastener, the combination of a ferrule projecting from the cue and having internal threads, a tip formed to have a bearing against the end of the ferrule, a block having faces provided with threads for engagement with said internal threads, said tip having inwardly and radially directed recesses, and arms movably associated with said block and having angular terminal portions for gripping engagement in said recesses.

4. In a billiard cue tip-fastener, the combination of a ferrule projecting from the cue and having internal threads, a tip having a shoulder to bear against the end of the ferrule and also having an extension within the ferrule for engagement with said threads, said extension having recesses in its engaging surfaces which terminate at their upper ends in inward and radial extensions, a block having faces provided with threads for engagement with said internal threads, and arms movably associated with said block and having angular terminal portions for gripping engagement in the extensions in said recesses.

5. In a billiard cue tip-fastener, the combination of a ferrule projecting from the cue and having internal threads, a tip formed to have a bearing against the end of the ferrule, a block having faces provided with threads for engagement with said internal threads, and arms connected in pairs by bows which form pivot bars and have transverse bearings in said block, said arms lying at the sides of said block and having in-turned terminal extensions, said tip having recesses in which said extensions engage to connect said tip and said block.

In testimony whereof we have hereunto set our hands in presence of two subscribing witnesses.

WILLIAM FEHLHABER.
CHARLES L. SMITH.
